UNITED STATES PATENT OFFICE.

KNUD CLEMENTSEN, OF CHICAGO, ILLINOIS.

LATCH.

SPECIFICATION forming part of Letters Patent No. 328,763, dated October 20, 1885.

Application filed August 24, 1885. Serial No. 175,230. (No model.)

To all whom it may concern:

Be it known that I, KNUD CLEMENTSEN, a subject of the King of Norway, and a resident of Chicago, in the county of Cook and State of Illinois, have invented certain new and useful Improvements in Latches; and I do hereby declare that the following is a full, clear, and exact description of the invention, which will enable others skilled in the art to which it applies to make and use the same, reference being had to the accompanying drawings, which form a part of this specification, and in which—

Figure 1 is a perspective view of a portion of a door provided with my improved latch. Fig. 2 is a longitudinal sectional view of the latch. Fig. 3 is an inside view of the latch, and Fig. 4 is a perspective detail view of the bolt and operating-lever.

Similar letters of reference indicate corresponding parts in all the figures.

My invention has relation to latches for swinging or sliding doors or similar objects; and it consists in the improved construction and combination of parts of the same, as hereinafter more fully described and claimed.

In the accompanying drawings, the letter A indicates the casing of the latch, the sides of which are formed with perforated lips B, for the passage of the fastening-screws C, and the rear portion of which casing is formed with a curved and looped handle, D, having a perforation, E, in its end for the passage of a fastening-screw, F.

The outer side of the casing is cut away to form a slot or aperture, G, through which the outer side of the sliding bolt H is exposed, the said bolt sliding in the casing, and this bolt is formed with a longitudinal slot, I, through which the operating thumb-lever J projects. The rear end of the bolt is reduced, as shown at K, and a spiral spring, L, is wrapped around this reduced portion, having one end resting in a recess, M, in the inner end of the casing, while its outer end bears against the inner end of the bolt, forcing it outward. The outer end of the bolt is beveled, as shown at N, having an inwardly-projecting lip, O, formed at the inner portion of the beveled end.

The inner end of the thumb-lever is provided with a cross-head, P, which rocks in bearings formed by two pairs of lugs, Q Q,

projecting from the edges of the recess of the casing, the said lips having their outer ends bent over the ends of the cross-head, so as to confine the same, and the outer end, R, of the thumb-lever is flat for convenient manipulation.

The face of the door has a recess, S, for the reception of the inwardly-projecting lugs and for the free passage of the inwardly-projecting lip upon the beveled end of the bolt, and the beveled end of the bolt may be introduced into and retained within the catch-plate T upon the door-jamb, when the door is closed.

It will be seen that this latch combines a handle with the latch, the curved or loop shaped handle serving as well as a handle in opening the door as for the purpose of giving the hand support in operating the thumb-lever, the loop-shaped handle affording a rest for the second or third finger of the hand while the thumb is pressed against the thumb-lever. By pressing the thumb-lever toward the inner end of the casing the bolt will be drawn in, and the spring in the casing will force the bolt out when the thumb-lever is released, so as to make the latch automatic.

The latch is preferably made of malleable metal, or, at all events, the casing is made of a malleable metal, so that the lugs forming the bearings for the cross-head of the thumb-lever may be bent over the ends of the same, and the entire latch is very simple of construction and composed of comparatively few pieces, which may be put together without the use of a great many tools or a large quantity of machinery, so that the latch may be manufactured at a comparatively low cost.

The latch may be used for all kinds of swinging doors, and may also, by making the head of the bolt square or beveled to another side, be used for sliding doors or other similar objects—as, for instance, it may be used as a sash-lock, secured upon the side rail of a sliding window-sash engaging a catch upon the window-jamb.

Having thus described my invention, I claim and desire to secure by Letters Patent of the United States—

1. In a latch, the combination, with a slotted casing having a pair of inwardly-projecting slotted lugs, of a slotted bolt sliding longitudinally in said casing, and a thumb-lever

having a cross-head at its inner end and passing through the bolt and casing, the ends of the slotted lugs being bent around the ends of the cross-head and forming bearings for the same, substantially as and for the purpose set forth.

2. The combination of a casing having an aperture in its upper side and formed with two laterally-projecting perforated lips and with a rearwardly-projecting curved loop-shaped handle and a pair of inwardly-projecting lugs at the edges of its recess, a bolt having a longitudinal slot and a reduced inner end and sliding in the casing, a spring wrapped around the reduced end of the bolt and bearing

against the inner end of the casing, and a thumb-lever having a cross-head at its inner end rocking in bearings formed by the ends of the said lugs, curved over the same, and projecting through the slot in the bolt and the aperture in the casing, as and for the purpose shown and set forth. 20

In testimony that I claim the foregoing as my own I have hereunto affixed my signature in presence of two witnesses.

KNUD CLEMENTSEN.

Witnesses:
